his Attorney

UNITED STATES PATENT OFFICE.

HENRY F. MORRIS, OF COLLINGSWOOD, NEW JERSEY.

SECTIONAL WATER GRATE.

Application filed March 3, 1921. Serial No. 449,524.

To all whom it may concern:

Be it known that I, HENRY F. MORRIS, a citizen of the United States, residing at Collingswood, in the county of Camden and State of New Jersey, have invented certain new and useful Improvements in Sectional Water Grates, of which the following is a specification.

This invention relates to sectional forced draft water grates and is an improvement upon Letters Patent of the United States No. 1,261,268 granted to myself and Ritner Shinn, April 2nd, 1918, and Letters Patent No. 1,348,235 granted to myself August 3rd, 1920.

An object of the present invention is to provide means in a sectional water grate to admit a greater volume of air to the fire at a very low pressure, lessening the cost of wear and maintenance of said grate, while retaining the stability and advantageous features of the grate described in the Letters Patents aforesaid.

This object is attained by the provision of an extension on one side of the water grate sections, through which extension holes or openings are cored or drilled as may be found necessary for increasing the volume of air to the quantity desired. These holes 20 may be of such number and area as may be required for the purpose stated. The said extension may be constructed in such shape, width or thickness that the heat therefrom will be absorbed by the water-body of the 30 grate, preventing the melting or warping of the structure of the said extension.

A further object of the invention is to provide a water grate of the class described whereby the sections comprising said grate 40 may be constructed with an extending portion or lip adapted to seat in a recess provided in the adjacent section.

A further object of the invention is to provide a water grate of the class described 45 that may be constructed in sections and means to firmly secure said sections to manifolds to provide for the continuous circulation of water throughout the grate.

A further object is to provide a grate of 50 the class described whereby an increased volume of air may be admitted thereto without increasing the pressure.

I attain these and other objects by means of the construction and arrangement of parts

illustrated in the accompanying drawings, 55 wherein:—

Figure 1 is a sectional plan view of a plurality of grate bars or sections secured to manifolds, on the line 1—1 of Fig. 2,

Figure 2 is an end elevational view illustrating a means of securing the grate sections in position,

Figure 3 is a transverse sectional view on line 3—3 of Fig. 1, and

Figure 4 is a perspective view, in cross 65 section, illustrating the perforated extensions on the side walls of the grate bars.

Like parts are referred to by like numerals throughout the drawings.

Referring to the drawings in detail the 70 numeral 10 denotes a forced draft water grate of the same general type as the grate described in Letters Patent No. 1,261,268 granted to myself and Ritner Shinn, April 2nd, 1918, provided with the individual 75 grate bars 14' having the cored openings or holes 14 for the passage of air and a water inlet pipe 11' at the front of said grate whereby water enters a manifold 11 and circulates thru the cored openings 23 in said 80 grate 10. A water outlet pipe 12' for the egress of water from a similar manifold 12 is provided at the rear of said grate 10, whereby the water after circulating thru said grate and being subjected to the heat 85 therein is carried off, thus providing for a continuous circulation of water thru said grate, preventing the overheating and melting thereof.

The individual grate bars or sections 90 23' containing the cored water portions 23 are secured to the manifolds 11 and 12 by means of the screw joint nipples 13, as illustrated in Fig. 1, insuring a water tight connection.

As a means for regulating the egress of 95 air from the cored openings 14, discs 15 provided with the openings 16 are shown. This is the method described in Letters Patent No. 1,261,268 hereinbefore cited.

The area of the opening 16 is determined 100 by the pressure of air to be exerted thereagainst. The greater the pressure the less the area of the said openings.

I find in practice, however, that when working under a low pressure, an increased 105 volume of air may be required, without increasing the pressure, over and above the fullest amount of air that may be had from

increasing to the fullest extent the area of the openings 16 in the discs 15.

With the construction shown in the present grate I provide the cored or drilled openings or holes 17 in the extension or lip 18 communicating directly with the draft of forced air, whereby a greater volume of air is admitted to the grate, the specific amount being regulated and determined by 10 the area and number of the openings 17.

In the construction shown in Fig. 4 an extension is made integral with a grate section and is adapted to seat or rest in a recess 19 provided in the adjoining or adjacent 15 grate section.

This method is followed in sequence with grate sections until the desired sized grate is assembled.

Plates 20 may connect the grate sections 20 at the base in pairs by means of set screws 22 and plates 21 may likewise connect the grate sections at the top in pairs by means of like set screws 22, so that said grate sections and plates form an unbroken series, 25 or said plates 20 and 21 may be used to secure adjacent grate sections together at the top and base, alternately.

The openings 17 in the extensions 18 may be made in various shapes and dimensions 30 as may be necessary to increase or decrease the volume of air to be admitted therethru and to provide for the absorption of heat passing therethru by the water circulating thru the openings 23; the walls normally 35 being of a thickness that will so permit, thus preventing the overheating of said extensions 18.

It will now be apparent that I have devised a novel and useful grate construction

which embodies the features of advantage 40 enumerated in the statement of the invention and the above description and while I have in the present instance shown and described the preferred embodiment thereof, which has been found in practice to give 45 satisfactory and reliable results, it is to be understood that the same is susceptible of modification in various particulars without departing from the spirit and scope of the invention or sacrificing any of its advantages. 50

Having thus described my invention what I claim as new and desire to secure by Letters Patent is:—

1. In a grate construction of the class described, a plurality of spaced grate bars, each grate bar having a lateral extension along one side thereof and a recess in its opposite side, said extension on each bar bridging the space between it and the next 60 adjacent bar and resting in the recess therein and plates securing adjacent bars together at the top and base, alternately, to hold same in position, substantially as described. 65

2. In a grate construction of the class described, a plurality of spaced grate bars, each grate bar having a lateral extension along one side thereof and a recess in its opposite side, said extension on each bar bridging the space between it and the next 70 adjacent bar and resting in the recess therein, plates securing adjacent bars together at the top and base, alternately to hold same in position and perforations in said 75 grate bars, substantially as described.

In testimony whereof I affix my signature.

HENRY F. MORRIS.
